UNITED STATES PATENT OFFICE.

ALBERT G. DAVIS, OF SCHENECTADY, NEW YORK, ASSIGNOR TO GENERAL ELECTRIC COMPANY, A CORPORATION OF NEW YORK.

AUTOMOBILE.

No. 890,615.

Specification of Letters Patent.

Patented June 16, 1908.

Application filed February 8, 1904. Serial No. 192,479.

To all whom it may concern:

Be it known that I, ALBERT G. DAVIS, a citizen of the United States, residing at Schenectady, county of Schenectady, and State of New York, have invented certain new and useful Improvements in Automobiles, of which the following is a specification.

My invention relates to automobiles, and has for its object to provide more efficient means for driving such machines, more simple, convenient and economical means for controlling the same, and a more compact and secure arrangement for the motive parts than has been obtained in automobiles as heretofore constructed.

In carrying out my invention, I provide a prime mover, such for instance as a gasolene engine, and an electric generator driven thereby, thus obtaining the convenience and flexibility of electric drive, and eliminating the necessity of using speed-changing gears.

One feature of my invention consists in the arrangement of the motor driven by the generator and its circuits, whereby operation at a number of speeds and a gradual variation of speed and torque may be readily and efficiently obtained with a single motor.

Another feature of my invention consists in an arrangement whereby all losses in the motor are prevented when the machine is running at full speed.

Another feature of my invention consists in an arrangement whereby the generator circuit is gradually opened upon the application of the brake, regardless of the position of the circuit controller.

Another feature of my invention consists in the mechanical arrangement of the motive parts, whereby the motive parts form a compact unit, efficient in operation and not liable to be thrown out of alinement or injured by jarring or straining on rough or uneven roads.

Other features of my invention will appear from the following specification and from the accompanying drawings, in which

Figure 1 shows a side view, with two wheels removed, of an automobile arranged in accordance with my invention; Fig. 2 shows a plan view of the same with the car body removed; Fig. 3 shows diagrammatically a controlling switch adapted to my invention

with the contacts developed in a plane; Fig. 4 shows a set of diagrams of circuit connections corresponding to the different positions of the controlling switch shown in Fig. 3; and Fig. 5 shows diagrammatically the brake pedal and the switch in the generator circuit controlled thereby.

Referring first to Figs. 1 and 2, A represents the main frame of the automobile, upon which is supported the car body B, and to which are secured in the usual manner the bearings for the wheels W.

C is an auxiliary frame, shown in Fig. 2, upon which are mounted the motive parts of the machine, and which is supported from the main frame A by a three-point suspension. Frame C may be secured at one end to frame A by bolts, as shown in Fig. 2, and at the other end may be supported from frame A by the hook or nose c, or by any other form of single-point suspension. The three-point suspension of auxiliary frame C from frame A insures that any strain or bending of frame A, due to rough or uneven roads, will not be transmitted to the auxiliary frame C and to the motive parts carried thereby.

Supported from frame C is the prime mover E which may be of any suitable type, such as a gasolene engine. Mounted on the shaft of the prime mover E is the revolving part or armature of the generator G, the stationary part or field of which is secured to frame C. The armature is placed outside of the field, as shown in Fig. 2, in order that the proportionate weight and the radius of gyration may be increased in order that it may act as a fly-wheel for the engine E. Also secured to frame C is the motor M, which is placed with its shaft in line with the engine shaft, and which carries at one end of its shaft one member of the clutch F. The other member of clutch F is carried by the engine shaft. With this arrangement the motor may be driven by the generator for the lower speeds, and when full speed is reached, the motor shaft may be clutched to the engine shaft and the motor circuit opened; thus saving all losses in the motor.

Although I have indicated a magnetic clutch, it is evident that any well known form of mechanically operated clutch may be substituted therefor if preferred. The rear end of the motor shaft drives the

differential gears D, which are connected through sprocket chains to the wheels in the usual manner. The arrangement of engine, generator and motor, in alignment and supported from a single frame, forms a compact unit of the motive parts, enables the engine shaft to be clutched directly to the differential gears without transmission losses, and insures the maintenance at all times of the proper relations between the motive parts.

H represents a band brake, which may be of any well known type, and which is operated through a bell-crank and through the rod h' by the brake pedal h shown in Fig. 1.

Referring now to Fig. 3, I shall describe a system of electrical control. The motor M is provided with two armature windings and two commutators in order that series parallel combinations may be obtained in a single machine. The two armature windings with their commutators are indicated diagrammatically at m m in Fig. 3. The motor field is indicated by m' and, as shown, has taps led to the controlling switch from both ends and from an intermediate point on the winding. The generator, which is indicated in Fig. 3 at G, and is there shown as a compound-wound machine, may be of any suitable type. f, in Fig. 3, represents the coil of the magnetic clutch; r represents a resistance in series therewith. The controlling switch, which may be operated by any convenient handle as I in Fig. 1, consists of the stationary contact-fingers i' to i", and the movable contacts as shown. The controlling switch, besides the off position, has six running positions. Positions 1 to 5, as indicated by the dotted lines, represent the forward running positions, while the position B' represents the backing position. The circuit connections, corresponding to the different positions of the controlling switch shown in Fig. 3, are shown in Fig. 4. Thus, in diagram B' x the circuit connections for position B' of the motor controlling switch are shown. The generator G is connected through the field m', and the two armature windings m of the motor in series. Diagram 1 x, corresponding to position 1 of the controller, shows the generator connected to the field and the two armature windings in series, with the direction of current through the armature windings reversed relative to diagram B' x. This is the slow-speed forward position. Diagram 2 x shows a portion of the field cut out, or short-circuited. The speed of the motor is consequently increased and this diagram corresponds to the second speed. In diagram 3 x, the two armature windings are shown connected in parallel with each other and in series with the whole field. In diagram 4 x, the armature windings are shown in parallel and a portion of the field winding short-circuited. This corresponds to the fourth or highest speed. When this speed is reached, the mo-

tor is running at approximately the same speed as the generator, and in order to save electrical losses in the motor, the clutch connecting motor shaft and engine shaft may be energized, and the motor circuit opened. This is accomplished at position 5 of the control switch, and the circuit arrangement is shown in diagram 5 x.

By the above described arrangement, a simple, efficient and convenient control of the automobile is provided, whereby a number of speeds may be obtained, the direction of movement reversed, and gradual acceleration from one speed to another secured.

In order to permit of quick stopping without the necessity for returning the controller handle to its off position, and also to prevent an application of the brake while energy is being supplied from the engine to the motor, I provide the arrangement shown in Fig. 5.

In Fig. 5, h represents the brake-pedal which controls the band-brake H through the connecting rod h', as has already been described. Mounted on the same shaft with the brake-pedal h and adapted to be engaged thereby is the crank or lever k, which is connected through the bell-crank k' and connecting rods to the switch member K. Switch member K is connected in the generator circuit, and when rotated on its axis engages consecutively the contacts connected to the resistance R, as shown. The normal position of switch member K is as shown in the figure. In this position resistance R is entirely cut out of the generator circuit. Now, if the brake-pedal h is depressed, tightening the band-brake H, switch member K is rotated toward the left, cutting in resistance R step by step, and gradually reducing the current in the generator circuit and consequently the power supplied to the motor, until when brake-pedal h is fully depressed, the extreme left-hand position is reached by switch member K and the generator circuit is opened. Thus, by the simple application of the brake, by means of the brake-pedal, the generator circuit is gradually, yet positively opened, regardless of the position of the handle I of the controlling switch.

I have now described a complete motive system and control therefor, for automobiles, comprising a number of features which, while I prefer to use them together, may with advantage be used separately, and which I desire to claim, whether used together or not. Moreover I have shown my invention embodied in a complete motor car, and for that purpose have shown a number of details which are not important to my invention, and which may be materially modified without departing from the spirit thereof. Accordingly, I do not desire to limit myself to the particular construction and arrangement of parts here shown, since changes which do not depart from the spirit of my invention,

and which are within the scope of the appended claims, will be obvious to those skilled in the art.

What I claim as new and desire to secure by Letters Patent of the United States, is,

5. 1. In a self-propelled vehicle, in combination with the frame thereof, a prime mover, an electric generator having its moving member mounted on the shaft of the prime mover, an electric motor having its shaft in line with the shaft of the prime mover, and an auxiliary frame supporting said prime mover, said generator and said motor, and suspended from the said vehicle frame.
10. 2. In a self-propelled vehicle, in combination with the main frame thereof, an auxiliary frame supported at three points from said main frame, a prime mover supported from said auxiliary frame, an electric generator having its stationary member supported from said auxiliary frame and its movable member mounted on the shaft of said prime mover, and an electric motor supported from said auxiliary frame and having its shaft in line with the shaft of said prime mover.
15. 3. In a self-propelled vehicle, a prime mover, an electric generator driven thereby, an electric motor having a plurality of armature windings, a switch adapted to connect said generator to said motor and to vary the relative connections of said motor windings, and means for clutching said motor to said prime mover.
20. 4. In a self-propelled vehicle, a prime mover, an electric generator driven thereby, an electric motor having a plurality of armature windings, and a controlling switch adapted to connect said generator to said motor, to vary the series-parallel connections of said motor and to vary the field ampere-turns of said motor.
25. 5. In a self-propelled vehicle, a prime mover, an electric generator driven thereby, an electric motor having two armature windings, a magnetic clutch adapted when energized to clutch said motor to said prime mover, and a controlling switch adapted to connect said generator to the motor armature windings in series, then to weaken the field of the motor, then to connect the motor armature windings in parallel and to strengthen the field of the motor, then to weaken again the field of the motor, and then to connect said generator to said magnetic clutch and to open the circuit of the motor.
30. 6. In a self-propelled vehicle, a prime mover, an electric generator driven thereby, an electric motor adapted to be driven by said generator, a brake, means for applying said brake, and means operative upon the application of the brake for opening the circuit of said generator.
35. 7. In a self-propelled vehicle, a prime mover, an electric generator driven thereby, an electric motor adapted to be driven by
40. 8. In a self-propelled vehicle, a prime mover, an electric generator driven thereby, an electric motor adapted to be driven by said generator, a brake, means for controlling said brake, and a switch in the circuit of said generator arranged to be operated upon the application of said brake.
45. 9. In a self-propelled vehicle, a prime mover, an electric generator driven thereby, an electric motor adapted to be driven by said generator, a brake, means for applying said brake, and a switch arranged to be operated upon the application of said brake and to introduce resistance gradually into the circuit of said generator.
50. 10. In a self-propelled vehicle, a prime mover, an electric generator driven thereby, an electric motor adapted to be driven by said generator, a brake, a pedal controlling said brake, and a switch in the circuit of said generator arranged to be operated by said pedal.
55. 11. In a self-propelled vehicle, in combination with the main frame thereof, an auxiliary frame supported at three points from said main frame, a prime mover, an electric generator, and an electric motor all supported from said auxiliary frame.
60. 12. In a self-propelled vehicle, a prime mover, a driven member, electric transmission mechanism between said prime mover and said driven member, a brake, means for controlling said brake, and means operative upon the application of the brake for opening the circuit of the transmission mechanism.
65. 13. In a self-propelled vehicle, a prime mover, a driven member, electric transmission mechanism between said prime mover and said driven member, a brake, means for controlling said brake, and means operative upon the application of the brake for inserting resistance in the circuit of said transmission mechanism.
70. 14. The combination of a prime mover, a dynamo driven thereby, a motor, electrical connections between the dynamo and motor, a driven member actuated by the motor, and means for locking the motor and dynamo together when the motor circuits have been adjusted for the maximum speed, whereby the power of the prime mover will be transmitted directly to the driven member, substantially as described.
75. 15. The combination of a prime mover, a dynamo driven thereby, a motor in axial alignment with the dynamo, electrical connections between the dynamo and motor, a driven member adapted to be actuated by the motor, means for locking the motor and dynamo together when the motor circuits have been adjusted for the maximum speed, whereby the power of the prime mover will be

transmitted directly to the driven member, and means for cutting the motor and dynamo out of circuit, when interlocked, substantially as described.

16. In combination, a prime mover, a primary shaft driven thereby, a driven member, a secondary shaft actuating the driven member, a dynamo operated from the primary shaft, an electric motor arranged to operate the secondary shaft, means for directly connecting the secondary and primary shafts, electrical connections between the dynamo and motor, and means for throwing the dynamo and motor out of electrical operation when the shafts are mechanically connected, and for throwing them into electrical operation when the shafts are mechanically disconnected.

17. In a power translating apparatus, the combination with a prime-mover, of a generator armature, a motor-armature, means by which the shafts of said armatures may be connected, and means providing a fixed point at which the aforesaid means may be actuated in the operation of the generator and motor armatures.

18. In a power translating apparatus, the combination with a prime-mover, of a generator armature, a motor armature, a clutch by which the shafts of said armatures may be connected, and means providing a fixed point at which the aforesaid clutch may be actuated in the operation of the said armatures.

19. A power translating apparatus, comprising a prime-mover, an electric generator, an electric motor receiving current from said generator, means whereby the armature shafts of the said generator and motor may be coupled together, and means providing a fixed point at which the aforesaid means may be actuated in the operation of said generator and motor.

20. In a power translating apparatus, and in combination, a generator armature, a motor armature, means for supplying the current from the generator armature to the motor armature, means for connecting and disconnecting the shafts of said armatures, and means providing a fixed point at which the last aforesaid means may be actuated in the operation of the said armatures.

21. A power translating apparatus, comprising a prime-mover, an electric generator, an electric motor, means for supplying current from the generator to the motor, means for controlling the torque and speed output of the motor, means for connecting the motor and generator armatures together mechanically, and means providing a fixed point at which the mechanical connection may be made in the operation of the motor and dynamo.

22. In a power translating apparatus, the combination with a prime-mover, of a gener-

ator armature, a motor armature, means for producing a magnetic flux through said armatures, a clutch for connecting the shafts of said armatures, and means for operating said clutch to connect the shafts when the motor circuits have been adjusted for maximum speed.

23. In a power translating apparatus, and in combination; a prime-mover, an electric generator, an electric motor, means for connecting the generator and motor electrically, means for connecting said generator and motor mechanically, and means for operating the last aforesaid means and regulating the magnetic flux in the fields of the electrical devices.

24. In a power translating apparatus, a source of power, a driven member, electrical means for operating the driven member by the source of power, mechanical means for operating the driven member by the source of power, and means rendering one of said means inoperative when the other is operative.

25. In a power translating apparatus, a source of power, a driven member, means whereby the driven member may be actuated electrically, means whereby the driven member may be actuated mechanically, and means providing a certain point at which the operation of the last aforesaid means may be effected in the operation of the electrical means.

26. In a power translating apparatus, a source of power, a driven member, electrical and mechanical means interchangeably available for operating the driven member by the source of power and means providing a certain point at which the operation of the aforesaid mechanical means may be effected in the operation of the electrical means.

27. In a power translating system, a prime-mover, a driven member, electrical and mechanical means interchangeably available for operating the driven member by the prime mover, controlling devices for varying the speed and torque delivered from the prime mover through said electrical means to the driven member, and means providing a certain point at which the operation of said mechanical means may be effected in the operation of the controlling devices.

28. In a power translating apparatus, the combination with a prime mover, of a generator armature, a motor armature, means for producing an electromagnetic flux through said armatures, means for regulating the electromagnetic flux through the motor armature, a clutch for connecting the shafts of the armatures together, and means for operating said clutch and controlling the means for regulating the flux through the motor armature so that the latter is inoperative when the clutch is operative, and vice versa.

29. In a power translating apparatus, the

combination with a prime-mover, of a generator armature, a motor armature, means for producing an electromagnetic flux through said armatures, means for regulating the electromagnetic flux through said armatures, a clutch for connecting the shafts of the armatures together, and means for operating said clutch and controlling the means for regulating the flux through the said armatures so that the latter are electrically inoperative when the clutch is operative, and vice versa.

30. In a power translating apparatus, the combination with a prime-mover, of a generator armature, a motor armature, means for producing a magnetic flux through said armatures, means for regulating the magnetic flux through said armatures, means by which the shafts of said armatures may be connected, and means providing a fixed point at which the last aforesaid means may be actuated in the operation of the generator and motor armatures.

31. In a power translating apparatus, the combination with a prime-mover, of a generator armature, a motor armature, means for producing a magnetic flux through said armatures, means for regulating the magnetic flux through said armatures, a clutch by which the shafts of said armatures may be connected, and means providing a fixed point at which the aforesaid clutch may be actuated in the operation of the said armatures.

32. In a power translating apparatus, the combination with a prime-mover, of a generator armature, a motor-armature, means electromagnetically operated by which the shafts of said armatures may be connected, and means providing a fixed point at which the aforesaid means may be actuated in the operation of the generator and motor armatures.

33. In a power translating apparatus, the combination with a prime-mover, of a generator armature, a motor armature, a clutch electromagnetically operated by which the shafts of said armatures may be connected, and means providing a fixed point at which the aforesaid clutch may be actuated in the operation of the said armatures.

34. In a power translating apparatus, a prime-mover, a driven member, a dynamo, a motor, an electromagnetically operated clutch for coupling the shafts of the armatures of said dynamo and motor together, means for producing a magnetic flux through the armatures of said dynamo and motor, means for controlling the magnetic flux through the armatures of said dynamo and motor for varying the speed of and the torque required of the motor, electrical connections between the respective terminals of the dynamo and motor, and electrical connections from the respective terminals of said clutch across the dynamo terminals in order that when the motor is operating at a slow speed

and considerable torque the clutch will be inoperative because of the low impressed electromotive force, and when the motor is operating at high speed and in considerable torque, the clutch will be automatically operated because of the higher impressed electromotive-force.

35. In a power translating apparatus, a source of power, a driven member, electrical means for operating the driven member by the source of power, mechanical means for operating the driven member by the source of power, and means providing a fixed point at which the operation of either of the aforesaid means may be effected in the operation of the other.

36. In a power translating apparatus, a source of power, a driven member, means whereby the driven member may be actuated electrically, means whereby the driven member may be actuated mechanically, and means providing a fixed point at which the operation of either of the aforesaid means may be effected in the operation of the other.

37. In a power translating apparatus, a source of power, a driven member, electrical and mechanical means interchangeably available for operating the driven member by the source of power, and means providing a fixed point at which the operation of either of the aforesaid means may be effected in the operation of the other.

38. In a power translating apparatus, a source of power, a driven member, electrical means for operating the driven member by the source of power, mechanical means for operating the driven member by the source of power, and means providing a fixed point at which the operation of either of the aforesaid means may only be effected in the operation of the other.

39. In a power translating apparatus, a source of power, a driven member, means whereby the driven member may be actuated electrically, means whereby the driven member may be actuated mechanically, and means providing a fixed point at which the operation of the aforesaid means may only be effected in the operation of the other.

40. In a power translating apparatus, a source of power, a driven member, electrical and mechanical means interchangeably available in operating the driven member by the source of power, and means providing a fixed point at which the operation of the aforesaid means may only be effected in the operation of the other.

41. In combination, a prime mover, a primary shaft driven thereby, a secondary shaft in axial alignment with the primary shaft, a driven part or member operated by said secondary shaft, a clutch between the primary and secondary shafts, and means for throwing said clutch into or out of operative position; with a dynamo operated by the

primary shaft, an electric motor arranged to operate the secondary shaft, electrical connections between the dynamo and motor, and means for throwing said dynamo and motor out of electrical operation when the secondary shaft is directly driven from the primary shaft.

In witness whereof I have hereunto set my hand this sixth day of February, 1904.

ALBERT G. DAVIS.
